UNITED STATES PATENT OFFICE

PAUL M. POPE, OF NEW YORK, N. Y., ASSIGNOR TO A. KIMBALL COMPANY, OF NEW YORK, N. Y., A CORPORATION OF NEW YORK

PRINTING MACHINE

Application filed January 30, 1929. Serial No. 336,115.

This invention relates to printing machines, particularly to machines for printing strips adapted to form a plurality of units such as identification or price tags or tickets. 5 One of the objects of the invention is the provision of an improved machine of this character which will be rapid and accurate in its operation and which will not damage the strips. 10 Among the more immediate objects of the invention is to avoid printing upon the backs of the tags from the platen,—stated another way,—to avoid inking the platen by the printing head when no tag is interposed therebetween; to avoid feeding more than one small tag in cases where the machine is also adapted to handle larger tags which are multiples of the smaller tag widths; and to provide improved means for guiding strips 15 of tags as they pass the printing position.

Other objects and various novel constructional features will be apparent from the following description of an illustrative embodiment of the invention when considered along 20 with the drawings thereof wherein:

Figure 1 is a top plan view of an assembled machine; 25 Figure 2 is a front elevation; Figure 3 is an enlarged section taken on the line 3—3 of Figure 1; Figure 4 is a partial top plan view of the front portion of the machine as seen from below the printing head, showing parts in initial position; 30 Figure 5 is a similar view showing the parts in final position;

Figure 6 is a side view of a platen slide shown in Figures 4 and 5, the position of the slide corresponding to that of Figure 4; 35 Figure 7 is a vertical section taken on the line 7—7 of Figure 1;

Figure 8 is a vertical section taken on the line 8—8 of Figure 7; Figure 9 is a vertical section taken on the line 9—9 of Figure 7; 40 Figure 10 is a vertical section taken on the line 10—10 of Figure 7;

Figure 11 is a section taken on the line 50 11—11 of Figure 9;

Figure 12 is a partial plan view showing the front left end of the machine;

Figure 13 is an elevational view partly in section taken on the line 13—13 of Figure 12;

Figure 14 is an enlarged elevational view 55 taken at the right end of Figures 1 and 2; and

Figure 15 is a vertical section taken on the line 15—15 of Figure 12.

The present invention is embodied in a printing machine similar to the one shown 60 and described in my co-pending application Serial Number 254,658, filed February 16, 1928. In that application the general purposes of the machine and the benefits obtained by it were discussed at length so need 65 not be reviewed in detail in the present application.

It will be well, however, to explain that the machine as a type is adapted to handle strips of tags of definite though varying 70 lengths, each strip usually comprising a fixed number of individual tags; that the machine embraces means for moving the strips in steps of a length equal to the width of one tag past a printing position where an impression is made, either original where the tag is blank or—and more usually—secondary to fill in blanks left for the purpose in a prior impression; and further that the tags may be and usually are partially severed 75 from each other and provided with strings, staples or other devices for attaching the tags to various articles.

Since staples comprise the attaching means most frequently employed at present, both 85 the prior application mentioned and the present one described an exemplary machine adapted to handle tags bearing staples. That is, the machines not only provide proper disposition of the staples so the tags will 90 lie flat for printing but also make use of the staples for guiding the strips of tags past printing position. Where other attaching devices are carried by the tags appropriate structural changes, if required, may be made 95 for handling them without departing from the invention described herein.

Coming now to a description of the present embodiment of the invention and referring first to Figures 1, 2 and 3, the machine com- 100

prises a base frame 20 provided with lugs or feet 21 adapted to rest upon a table, frame or other suitable foundation on which the machine is to be placed. The machine is 5 relatively small and light and may be transported from place to place by one person in the same manner as a typewriter or computing machine.

Upon the top of the frame 20 several 10 plates 22, 23, 24 and a front strip 26 are secured in any suitable manner so that their top surfaces together form a smooth and plane table over which the strips of tags 27, indicated in dotted lines, travel. The plates 15 23, 24 which are made fast to the frame 20 are spaced from each other so as to provide a recess or groove 28 for the reception of the protruding ends of the staples carried by tags of a certain size in order that the strips 20 may lie flat on the table and be guided past printing position. If no staples are present the guide means will conform to the type fastenings used, or the gripper mechanism hereinafter to be described may hold the 25 strips sufficiently secure to guide them satisfactorily past printing position. The plates 23, 24 terminate at a desired line across the table to accommodate a print pad or platen 33 (Figure 3) the top surface of which is 30 flush with the top of the table. The platen is carried (see especially Figure 6) by a plate 25 secured beneath and extending beyond the right end of the plate 24.

In accordance with this invention means is 35 provided for carrying the strips of tags in a step-by-step movement past the printing position as represented by the print pad 33 and providing for the accurate positioning of the individual tags in the printing position. It is also proposed to provide means 40 which may be a part of or associated with the feeding means for handling strips of tags of different sizes. In the particular embodiment herein to be described four different 45 sizes of tags can be handled but obviously provision may be made for handling a greater number of sizes if desired.

While the means mentioned above may have many different embodiments, that 50 which is at present preferred and which will be described herein, comprises a gripper device generally denoted by the numeral 40 and means for moving the same as required. Any selected means may be provided for imparting to the gripper device an intermittent or step-by-step forward movement to carry the strips of tags past the printing position but, as herein shown and described, this moving means comprises a reciprocating 55 feed bar 41, which bar may be actuated by any suitable mechanism. Referring to Figures 12 to 15, the gripper device comprises a block 42 slidable between a faced vertical wall 43 and the strip 26, which strip 60 is spaced from the wall 43 so as to form a

guideway from the printing position to the left end of the frame. The block 42 thus is guided to travel from printing position, to the left end of the apparatus where it is stopped (Figure 4) by a spacer block 45 70 supporting the end of strip 26 upon the frame 20. The strip 26 is somewhat resilient and bears with a slight pressure upon the side of the block 42 so that the latter will frictionally hold its position at any point to which it is moved except when a slight force is applied to move it.

Means is provided on the block 42 for gripping the ends of the strips of tags and, while this means may assume different embodiments, it is shown as a flexible finger 46 secured to a block 47 which is pivoted to the sliding block 42 by a pin 48. A coiled spring 49 disposed within a recess 50 in the block 42 bears against the bottom of the recess and against the block 47 below the pin 48 to bias the finger 46 at all times against the upper surface of the sliding block 42. The block beneath the end of finger 46 may be roughened as at 51 to assist the holding action of the finger. Strips inserted between the finger and the block 42 will be firmly held and drawn forward in accordance with the movements of the sliding block. A pin or stud 52 may be secured in the sliding block 42 along the length of the finger 46 to fix the position of the strips therebeneath. Preferably the pin 52 is also disposed intermediate the width of the finger 46. For example, it may pass through a hole 53 in the finger, the hole being somewhat larger in diameter than the outside diameter of the pin for freedom of movement.

Although any suitable means may be employed for causing the gripper device 40 to be moved in one direction and one direction only by the feed bar 41, the means here selected comprises a pawl 55 pivoted to the block 42 by a pin 56 in such position that its offset end 57 may move into engagement with suitable operating members provided on the reciprocating feed bar. The free end of the pawl is heavier than the operating end 57 so that the latter will be biased by gravity toward the feed bar.

It is desirable to free the gripper device from the feed bar at certain times in order that it may be moved up past the printing position to engage a fresh strip of tags. For this purpose the pawl 55 is arranged to be disengaged or moved clear of the push rod by a cam 60 fixed on a hand rotated rod 61 mounted on the block 42. The cam 60 is provided with a flat face 62 disposed within a notch 63 of the pawl. The other portion 64 of the cam is concentric and when the pawl is raised by this concentric portion its operating end 57 will be clear of the feed bar.

Means is associated with the hand operated rod 61 for lifting the gripper finger 46

when the pawl is disengaged from the bar. This may be accomplished by providing a pin 65 in a bore 66 in the block 42 between the end of the pawl 55 and the finger 46. By this arrangement the pin which constantly rests upon the top surface of the pawl will engage the under surface of the finger 46 upon upward movement of the weighted end of the pawl. It is arranged that the finger 46 will be lowered to engage the strip of tags slightly before the pawl engages the feed bar. This is done in order that the gripper device will not be moved away by action of the feed bar until the strip of tags is securely caught by the finger.

10 A knob 67 may be provided on the outer end of the rod 61 to enable the same to be readily moved by an operator. If desired the rotative movement of the rod 61 may be limited by a notched disk 68 fast on the rod 61 cooperating with a stud 69 fixed in the block against which one of the two abutments of the notch in the disk may strike.

15 The feed bar 41 may be constructed in various ways so as to impart movement to the gripper device. As shown the means comprises several (four as shown) sets of equally spaced notches 71, the spacing of the different sets of notches, however, being different 20 to provide the correct feeding for tickets of different widths. The set of notches 71a, for example, may be of one spacing; the notches 71b of a slightly longer spacing; the notches 71c of still longer spacing and the notches 71d of the longest spacing. The four sizes 25 provided will take care of the principal tag sizes at present employed but if further tag sizes are to be handled, it will be obvious that other sets of notches may be provided on 30 the feed bar by making the same of larger diameter or by allotting less of the peripheral length to each set.

35 According to the present invention means is provided for rotating and locking the feed bar 41 so that any one of the several sets of notches may be instrumental in actuating the sliding gripper device. As shown in Figures 1, 2, 7 and 14 this means may comprise a sleeve or bushing 73 suitably mounted in a bore 74 in the end of the base frame and slidably keyed to the feed bar 41. The sleeve 73 may be provided with a head 75 having longitudinal slots 76 therein. A stud 77 fixed in the base frame is arranged to engage the head 75 within one of the notches 76 when the head is pushed forward but when the head is moved outward, it is released from engagement with the stud 77 and may be rotated so that another notch 76 will engage 40 the stud. A hand screw 78 having a head 79 adapted to bear against the outer end of the head 75 of the bushing may be employed to hold the same in forward position in engagement with the stud 77.

45 According to this invention suitable means

is provided for causing reciprocation of the feed bar 41. Preferably it is arranged that the feed bar will be moved in feeding direction by a spring or other resilient means while it is moved in the reverse direction by 50 positively actuated means. As shown (Figures 1, 2, 3 and 7) the operating means may comprise a lug or collar 80 fast on the feed bar 41 and a coil spring 81 disposed between the end of the collar 80 and the end of the sleeve 73. A lever 82 pivoted to the base frame by a pin 83 has an end 84 adapted to engage the collar 80 and to operate the feed bar against the spring. A cam 85 on a vertical shaft 86 may be employed to actuate the lever 82 as by engagement with roller 87 mounted upon a pin 88 in the outer end of the lever 82. A projection or abutment 89 may be provided on the outer end of the lever 82 for engagement with the end of a set screw 90. By adjusting the set screw 90 the movement of the roller end of the lever 82 toward the cam 85 may be limited. This will limit the permissible movement of the collar 80 and the feed bar 41 and, through the gripper device, will serve to accurately position the tags upon the printing pad.

55 Suitable means is herein provided for printing the tags as they are successively positioned upon print pad 33. The means illustrated comprises a printing head 95 mounted upon arms 96 journaled upon a pin 97 in standards or brackets 98 bolted or otherwise secured to the frame 20. An arm 99 integral with arms 96 may be connected with suitable mechanism for operating the printing head. The arm 99, as here shown, carries a pin 100 operating in a bearing in one end of a connecting rod 101, which rod is driven by a crank pin 102 carried upon the face of a gear 103. Means may be provided for adjusting the length of this connecting rod in order that the type carried by the printing head may at all times engage the strips.

60 Both the feeding mechanism and the printing mechanism may be operated by a motor M through suitable gearing. For example the motor shaft 104 may carry a pinion 105 engaging a gear 106 fast on a lay shaft 107, which latter shaft carries a pinion 108 engaging the gear 103 to which the crank 102 is affixed. The gear 103 may be fixed to a shaft 109 supported in a bearing in the bracket 98. This shaft may also carry a bevel gear 110 meshing with a similar bevel gear 111 fast on the shaft 86 driving the feed lever operating cam 85.

65 The printing head 95 may comprise a plate 114 attached to the two arms 96 and a chase holder 115 having a closed end 116 and ribs 117 along which the chase 118 slides. The chase may have a knob 120 so that it may be readily handled. It may be locked in the chase holder by a latch 121. The chase holder is secured to the plate 114 by two bolts 122

130

passing through slots 123 in the latter. By this arrangement the chase holder may be moved laterally of the path of movement of the tags so that the type may be accurately located with respect thereto. Also, the chase may be quickly removed and its type changed for different jobs.

Means is herein provided for inking the type when it is moved away from printing position. This mechanism is shown quite clearly in Figure 3. The full lines in that figure show the mechanism in printing position and the dot and dash lines show it in off or inking position. This inking means 10 may comprise an ink pad 126 adapted to be attached by a clip 127 to a bar 128 rigid with the arm 129. The arm 129 may be pivotally supported through a pin 130 at its upper end by a bracket 131 affixed to the base 20 while 20 the arm 129 at its lower end is connected by a link 132 with the printing head. The connection of the link 132 with the arm 129 may be made through a pivot pin 133 while the other end of the link 132 may be pivoted to a 25 fixed pin 134 fast on the printing head. By this arrangement movement imparted to the printing head through the connecting rod 101 will cause the ink pad to swing upward and strike the type face to face and 30 ink the same. The ink pad, however, when swinging outwardly as the printing head moves down, will stand above the strips of tags and the gripper mechanism.

The tags 27 indicated in dotted lines in 35 Figure 1 are relatively short but the machine is adapted to handle tags of greater length and to print the tags on either end. For this purpose guides are provided both at the front and rear sides of the supporting table. These 40 guides include the strips 136, 137 spaced apart to provide a groove 138 to accommodate the staples. The leading ends of the strips 137 may be bent outwardly as indicated at 45 139 to guide the staples into the grooves. The top edges of the strips 136, 137 are arranged at the same height as the top of the table so as to constitute in effect an extension thereof. The strips 136, 137 may be adjusted in position 50 relatively to the front and rear edges of the table and to this end they are mounted by collars 141 slidable upon fixed rods 142 and held in adjusted positions thereon by thumb screws 143.

Means is herein provided for guiding those 55 strips whose staples coincide with the groove 28 (between the plates 23, 24) after the rear ends of the strips pass the end of the groove at the printing position. As illustrated in Figures 4, 5 and 10, a guide block 150 is slidably mounted in the guideway constituted by the wall 43 and the strip 26 quite like the gripper block 42 is mounted therein, the guide block 150, however, being mounted between the gripper block and the ends of the 60 strips 151 in the plates 23, 24. In its upper 65 jogs 151 in the plates 23, 24. In its upper

surface the guide block has a groove 152 which is aligned with the groove 28 and in effect forms a continuation thereof.

When the gripper block is moved to its extreme right hand position to grasp a new 70 strip of tags it pushes the block 150 to the right. The guide block is provided with a socket 153 and the gripper block is provided with a mating resilient stud 154. This stud enters the socket 153 when the two blocks 75 meet in moving to the right and forms in effect a coupling which carries the guide block back to the left with the gripper block as it moves to the left.

A stop rib 155 on the guide block strikes 80 the end wall of a groove 156 in the strip 26 in this left hand movement which uncouples the two blocks. The gripper block travels on to the left while the guide block is left in front of the printing platen where it guides 85 the staples of the trailing end of the strip past printing position.

Means is provided for insuring that the platen is not inked by the printing head. Referring to Figures 4 and 5, the means provided for this purpose while the gripper block is engaging a fresh strip of tags comprises a cover plate 160 secured to the gripper block and adapted to overlie the platen. The mounting of this plate on the block and its disposition over the table are best shown in 90 Figure 15. The plate being quite thin, will not limit the normal travel of the printing head, its thickness in fact being only slightly greater than the thickness of the tags. 95

After the strip of tags passes printing position it again becomes necessary to protect the platen against inking. Preferably this is accomplished by moving the platen out of the path of the printing head after the last tag 100 of the strip has been printed.

Referring to Figures 4 to 11, the plate 22 is slidably mounted on the frame, being provided with undercut slides 165, 166 operating within correspondingly shaped guides in the left end wall 167 and an intermediate cross wall 168 respectively of the base frame 20. 110

The slide 165 is attached to the plate by countersunk rivets 169. The slide 166 is formed (Figures 5, 6) as an extension of the auxiliary platen-supporting plate 25 attached to the plate 22 by countersunk rivets 169. 115

Still referring to Figure 6, the plate 25 on its lower surface carries a shift block 170 by which the plate and platen assembly is moved to the right as by (Figures 6 and 7) an upstanding shift pin 171 carried by the gripper block 42. 120

The plate and platen assembly is moved to 125 the left (carrying the platen away from printing position) by any suitable means. Herein the previously mentioned platen cover plate 160 is given this additional function. This plate (Figures 1 and 7) comes 130

against an adjustable shift plate 173 when the last tag of a strip has been printed and with the next movement of the gripper block moves the platen to the left.

The shift plate is adjustable to take care of different tag strip lengths, it having been remarked previously that each strip preferably contained the same number of tags. As shown in Figures 9 and 11 the shift plate 173 is hooked as at 174 at each end to slidably embrace the plate 22. A setting block 175 secured upon the plate carries a setting pin 176 adapted to enter spaced holes 177 along the plate 22 for holding the shift plate at various positions (refer to Figure 1) designated 1, 2, 3, 4, H, etc. corresponding to the lengths of the strips. A sight opening 178 in the shift plate permits visibility of the mark on which the plate is set.

Means is provided for preventing over-feeding of narrow tags. This may be accomplished in various ways. As shown in Figure 7 a notch 180 is formed on the feed bar 41 to cooperate with a dog 181 pivoted as by a pin 182 to the frame 20.

This notch corresponds in use with the intended tag feeding notches on the bar, although as shown it may be located on the opposite side of the bar from the feeding notches. The dog limits the travel of the feed bar to the left by engaging the notch. Since the bar is urged to the left only by the spring 49 there is no interference with normal operations by the travel limiting mechanism. It is also to be observed that the travel limiting mechanism will always function properly for the intended tag strips without attention by the operator since the dog (which normally remains down) and notch always coincide when the feed bar is turned to proper position for tags of that size.

By throwing the dog over in the reverse direction the feed mechanism will take care of double width tags since the feeding mechanism is then allowed to operate two notches at a time.

If desired (Figures 1 and 2) a shield 185 acting as a tag guide and hand protector may be provided on the feed side of the printing head. This guide may be supported by an arm 186 swingably carried by a pivot post 187 in order that the shield may be moved out of the way when necessary.

The foregoing description is believed to be sufficiently explicit to warrant the omission of a recapitulation of the operation of the machine.

Although one embodiment of the invention has been described in considerable detail, it is to be understood that various changes and modifications may be made within the scope of the appended claims.

What I claim is:

1. Apparatus of the character described comprising in combination, an oscillatory

printer, a printing platen, a slideable plate supporting said platen, a slideable device for gripping a strip of tags and moving it past the printer, a part carried by said device for covering said platen while a strip is being engaged, cooperating members on said device and slideable plate adapted to move the platen beneath the printer after it has been covered by said part, and an adjustable element on said slideable plate cooperating with said cover part to shift the platen away from said printer when the strip of tags has been completely printed.

2. Printing apparatus including in combination, a printing device, a platen cooperating therewith, means for engaging a strip at one side of said platen and moving it in successive steps past the platen, means on said strip-moving means for shifting and covering said platen when engaging a strip and for again shifting the platen when the strip has passed.

3. Printing apparatus including in combination, cooperative printing devices at a printing position, means for moving strips past said printing position, means associated with said strip-moving means for shifting one of said printing devices into cooperative relationship and for dissociating said devices when the strip-moving means is in one position, said associated means also shifting one of said printing devices out of cooperative relationship with the other when the strip-moving means is in another position.

4. Printing apparatus including in combination, a platen, means for moving strips in successive steps past said platen, means associated with said strip-moving means for shifting said platen, and means associated with said platen and cooperating with said shifting means providing adjustment for timing the shift of said platen for strips of various lengths.

5. Printing apparatus including in combination, a platen, means for moving strips past said platen, means associated with said strip-moving means for shifting said platen, and means associated with said platen and cooperating with said shifting means providing adjustment for changing the point at which the platen is shifted.

6. Printing apparatus including in combination, a printing device, a platen cooperable therewith, means for moving a strip of tags past said platen, and means associated with said strip-moving means for separating said printing device and platen at times, said separating means including a member adapted to cover said platen and to shift said platen.

7. Printing apparatus including in combination, a printing device, a platen cooperable therewith, means for moving a strip of tags in successive steps past said platen, and means associated with said strip-moving means for separating said printing de-

vice and platen at times, said separating means including a means for shifting said platen relative to said printing device.

8. Printing apparatus including in combination, a printing device, a platen cooperable therewith, means for moving a strip of tags past said platen, and means associated with said strip-moving means for separating said printing device and platen at times, said separating means including a cover for said platen.

9. Printing apparatus including in combination, a printing device, a platen cooperable therewith, means for moving a strip of tags in successive steps past said platen, and means associated with said strip-moving means for separating said printing device and platen at times.

10. Apparatus of the character described comprising in combination, printing means, a platen cooperating with said printing means, means for moving a strip between said printing means and platen, and means providing a separation between said printing means and platen when a strip is not disposed therebetween, said means including a member movable at times into position between the printing means and platen and mechanism operable at times for removing said platen out of cooperative relationship with said printing means.

11. Apparatus of the character described comprising in combination, printing means, a platen cooperating with said printing means, means for moving a strip between said printing means and platen, and means providing a separation between said printing means and platen when a strip is not disposed therebetween, said means including mechanism for removing said platen out of cooperative relationship with said printing means.

12. Apparatus of the character described comprising in combination, printing means, a platen cooperating with said printing means, means for moving a strip between said printing means and platen, and means providing a separation between said printing means and platen when a strip is not disposed therebetween, said means including a member movable into position between the printing means and platen.

13. Apparatus of the character described comprising in combination, printing means, a platen cooperating with said printing means, means for moving a strip between said printing means and platen, and means shiftable transversely by the extent of the printing width of the printing means providing a separation between said printing means and platen when a strip is not disposed therebetween.

14. Apparatus of the character described for performing intermittent printing or related operation upon a strip of uniformly spaced tags comprising in combination means

located at a definite station for intermittently performing the operation on said strip, a table along which the strip may move, a strip engaging device, means for moving said device step-by-step for feeding the strips, said means including elements adapted selectively to accommodate for steps of several different lengths, and means associated with said feeding means for automatically limiting the movement of said device when short steps are taken.

15. Apparatus of the character described for performing intermittent printing or related operation upon a strip of uniformly spaced tags comprising in combination means located at a definite station for intermittently performing the operation on said strip, a table along which the strip may move, a feed bar adapted to accommodate a plurality of different stroke lengths, an arm for operating said bar in one direction, said bar having a constant stroke as great as the greatest required stroke of said bar, a spring urging said bar in the other direction, and means for selectively limiting the stroke of said bar at times.

16. Apparatus of the character described for performing intermittent printing or related operation upon a strip of uniformly spaced tags comprising in combination means located at a definite station for intermittently performing the operation on said strip, a table along which the strip may move, means for selectively feeding tags of different widths and means associated with said feeding means for limiting its action to prevent overfeeding tags of narrow width when such tags are half or less than half the width of wider tags accommodated.

17. Apparatus as set forth in claim 16 in which said action-limiting means comes into service automatically upon setting said feeding means for narrow tags.

18. Apparatus as set forth in claim 16 in which said action-limiting means may be rendered inoperative to adapt the feeding means for feeding tags of widths which are multiples of the narrow tag widths.

19. Apparatus of the character described for performing intermittent printing or related operation upon a strip of uniformly spaced tags comprising a reciprocable feed bar, a plurality of linear sets of notches on said bar, a device adapted to be moved in steps selectively by various ones of said sets of notches, and a dog engageable with said bar when acting through a given set of notches to limit its reciprocation.

20. Apparatus of the character described, comprising printing means, a table having a groove for guiding a staple-bearing strip to said printing means, a strip feeding device movable to a position adjacent said printing means for engaging a strip, and means for guiding the trailing ends of strips past said

printing means, said guiding means being movable to make way for said strip-feeding means.

21. Apparatus of the character described comprising in combination a printing device, a guideway alongside said printing device, a strip guide surface at one side of said printing device beyond the end of said guideway, a staple groove in said guide surface terminating in said guideway, a feeding device movable in said guideway to a position alongside said printing device, a staple guide block also slidably in said guideway and having a groove aligning with said table groove, said feeding device having a breakable traction coupling with said block established when said feeding device is moved alongside the printing device, said feeding device pulling said block with it on return movement, and means to break said coupling and leave said block alongside said printing device.

22. Apparatus of the character described, in combination, printing means at a printing station, a slidable strip feeding gripper block for moving strips past said station, a slidable strip guiding block having a limited movement with reference to said station, and a resilient traction coupling between said blocks for imparting to said guiding block its limited movement by movement of said gripper block.

23. Apparatus of the character described, in combination, printing means at a printing station, a slidable strip feeding gripper block for moving strips past said station, a slidable strip guiding block having a limited movement with reference to said station, and a resilient traction means between said blocks for imparting to said guiding block its limited movement by movement of said gripper block, said means including a resilient stud on one block and a cooperating socket on the other block.

24. Apparatus of the character described comprising in combination, a printer, a platen, and means shiftable transversely by the extent of the printing width of the printing means for preventing the inking of said platen by said printer.

50 In testimony whereof, I have signed my name to this specification this 24 day of January, 1929.

PAUL M. POPE.
